INVENTOR:

Samuel W. Bevans

United States Patent Office.

SAMUEL W. BEVANS, OF PLYMOUTH, CONNECTICUT, ASSIGNOR TO HIMSELF
AND GEORGE A. MUNSON, OF SAME PLACE.

Letters Patent No. 76,982, dated April 21, 1868.

IMPROVED FEATHER-DRESSING MACHINE.

The Schedule referred to in these Letters Patent and making part of the same.

TO ALL WHOM IT MAY CONCERN:

Be it known that I, SAMUEL W. BEVANS, of Plymouth, county of Litchfield, and State of Connecticut, have invented certain new and useful Improvements in Feather-Dressing Machines; and to enable others skilled to make and use the same, I will proceed to describe, by referring to the drawings, in which the same letters indicate like parts in each of the figures.

The nature of this invention will be understood from the specification and drawings.
Figure 1 is a sectional side view.

Figure 2 is a section end view, cut through the centre of the cylinder.

a is the body of the cylinder, formed round or octagon shape, as may be desirable.
a' are the heads of the cylinder.

a'' is a door or orifice, through which the material or feathers are introduced into the machine.

b is a hollow shaft, which extends through the cylinder, and is secured to the heads thereof by means of flanges, and extends through said heads or flanges, so as to form bearings, to support and at the same time allow the cylinder to rotate thereon. This shaft *b* is provided with valves or an inner hollow tube, *c*, having orifices, *d*, corresponding with the orifices *d* in the shaft *b*. This inner shaft is fitted closely into the main or outer shaft *b*.

e is a central shaft or spindle, secured inside of the shaft *c* by brackets or cross-bars, *f*, by means of which the valves or inner shaft may be turned, to open or close the ports *d*, by applying a key or wrench to the outer end, which extends outward, through the packing-boxes or other mode of closing the outer ends of the shafts, which, with the mode of introducing steam into the shaft, is designed to be effected in the usual way.

The body of the shaft is bilged, and has a central discharge-orifice and tube, to conduct the fluid or exhaust steam from the cylinder, so as to secure a perfectly dry atmosphere, and thereby aid to more perfectly clean the material or feathers, and to greatly facilitate the operation of cleansing.

Having thus shown the nature, construction, and advantage of this invention, I will state what I claim.

What I claim, and desire to secure by Letters Patent, is—

In a feather-dressing machine, attaching a discharge-tube in or near the centre of the bilge or cylinder, substantially as and for the purpose described.
